(57) **CLAIM**

The ornamental design for a golf ball retriever, as shown and described.

DESCRIPTION

FIG. 1 is a perspective view of a golf ball retriever showing my new design in association with its environment;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines shown in FIG. 1 are included for the purpose of illustrating the environment of the golf ball retriever and form no part of the claimed design.
